UNITED STATES PATENT OFFICE.

HARRY L. OWEN, OF YORK, PENNSYLVANIA, ASSIGNOR TO GENERAL ELECTRIC COMPANY, A CORPORATION OF NEW YORK.

ROTARY COMPRESSOR FOR WIRE-COVERING MACHINES.

1,053,061.

Specification of Letters Patent. Patented Feb. 11, 1913.

Application filed January 20, 1909. Serial No. 473,244.

To all whom it may concern:

Be it known that I, HARRY L. OWEN, a citizen of the United States, residing at York, in the county of York and State of Pennsylvania, have invented certain new and useful Improvements in Rotary Compressors for Wire-Covering Machines, of which the following is a specification, reference being had therein to the accompanying drawing.

My invention relates to a machine for covering wire with an insulating material, such as asbestos fiber, or other suitable material, and in such connection it relates particularly to that step in the process known as compressing the fiber upon the wire, or in other words, the insulation compressor. Most of the machines now employed for this purpose are unsatisfactory owing to the fact that the wire is conveyed from the stock reel around numerous corners which tend to bend and harden the wire which has been found very detrimental to the uses for which the wire is intended; and furthermore, the asbestos fiber is often loosened and stripped from the wire by the rollers or compressors now in use. By none of the devices now employed can it be evenly compressed upon the wire, owing to the lumps of foreign matter adhering to the compressor. Also in many of the machines for this purpose now in use the wire as it progresses or is drawn through the machine is constantly revolved and passed through dies and straightening devices which are detrimental and to a certain extent destroy its qualities.

By my invention the wire is drawn and progresses through the covering machine in a straight line from the stock reel and without being axially revolved, and by my novel construction of coverer for applying the insulation which is revolved about the wire, the asbestos fiber is applied in an overlapping spiral about the wire and in a perfectly even state and retaining all of its flocculent qualities as received from the doffer rolls of the carding machine by the use of my special carriers or tape reels, which are fully described in my application for a "method of conveying and preparing asbestos fiber" filed Jan. 20, 1909, Serial No. 473,245.

The objects of my present invention are to produce a compressor for compressing

the asbestos fiber or other suitable material upon the wire or other electric conductor, (which may be in cross section of any desired shape) as an insulating coating, the wire being drawn through the machine without being revolved upon its axis and the covering material and compressor being revolved about the wire during its application thereto.

With these and other objects in view my invention consists in certain construction and combination of parts as will hereinafter be fully described and claimed and as illustrated in the accompanying drawings in which like reference numerals indicate corresponding parts in all of the views. However it is fully understood that while I have here described and claimed my invention as herewith illustrated, I do not confine myself to the exact design as shown, as slight changes may be made in the construction and combination of parts without departing from the spirit of the invention.

Referring to the accompanying drawings forming a part of this application:—Figure 1, is a side elevation of a wire covering machine embodying the present invention. Fig. 2, is a partial detail end view of the same, showing the compensating mechanism to operate the wire winding reel. Fig. 3, is an elevation of one face of the compressing machine for compressing the insulating material upon the wire. Fig. 4, is a side elevation of the same with part of the case or housing removed. Fig. 5, is a top plan view of the same, taken on the line X—X of Fig. 3.

In the drawings:—1, indicates a suitable supporting frame upon which are mounted, first, the stock wire reel 2, from whence the bare wire or conductor 3, is drawn by having been given one complete wrap around the peripheral groove in the sheave wheel 4, which is operated by the worm wheel 5, meshing with the worm 6, mounted upon the driving shaft 7. The wire 3, after leaving the reel 2, is drawn through the guide 8, and the straightening die 9, of any suitable design and thence above and in contact with the revolving adhesive composition applying wheel 10, which is revolved within the composition pot 11, by the sprocket chain 12, driven from the main driving shaft. The wire now having been coated with adhesive composition is drawn through the

center of the covering or asbestos applying machine 14, which forms the subject of another application and which will be therein fully described and claimed. After leaving the coverer, above referred to, the wire now passes under the drip pot 13, which applies the outer coating or waterproofing material, but this may be dispensed with if desired, as by my method it will not be found necessary. Directly in the rear of said compressor is situated the cooler or heater, as the case may be, and which is shown here as a cooler 15, for cooling the coating composition applied by the drip pot 13; or if a heater is employed, for baking said coating material upon the wire. The wire is now led around the friction drawing wheel, before referred to, which draws the wire through the machine by friction and thence between the guide rollers 16, and to the winding reel 17, upon which it is wound as the same is rotated by the action of the belt 18, which runs over the pulley 19. The object in employing a belt is that it will slip to compensate for the variation of speed attained by the reel 17, due to the positive delivery of the wire from the friction wheel, and the increasing diameter of the wire upon the reel 17.

30 The compensating mechanism for the wire winding reel 17, consists in the shaft 20, provided with the right and left handed screw-threads and journaled in the bearings 21, situated on the supporting frame 1. One 35 end of said shaft is formed with the spline 22, to allow the driving pulley 23, to freely slide thereon and yet rotate said shaft by the engaging feather. To the end of the frame 1, is pivoted the balance arm 24, which 40 has attached thereto the shifting lever 25, which has its ends pivoted to the outer ends of the levers 26, which are mounted upon the extension 27, of the bearing brackets 21. The bearing brackets have attached to their 45 inner ends the half screw-threaded boxes 28, which are thrown in and out of engagement with the threaded shaft 20, and which by their engagement with said shaft 20, draw the wire winding reel either to 50 the right or left, for, as the wire is wound upon the reel, it travels from one side toward the other as caused by the successive wraps thereon, and as it passes the center of the reel 17 the balance arm 24 is thrown 55 over, thus bringing the proper screw-threaded box into mesh with the thread of the shaft to convey the reel 17, in the proper direction to accommodate the wraps of wire, and it will, therefore, be seen that this action is entirely automatic.

The asbestos applying mechanism may be of any suitable construction, but is preferably and here shown of my novel design as covered by an application for Letters Patent filed Jan. 20, 1909, Serial No. 473,243

and entitled, a "Rotary asbestos applier for wire-covering machines."

Referring to the subject of this application the rotary compressor comprises a housing or case 29, which is divided horizontally through its center into two members, the lower member being secured upon the supporting frame 1, and provided with the bearing brackets 30, in which are rotatably mounted the shafts 31, which carry the V-shaped friction wheels 32, and the sprockets 33, which are connected together by the chain 34; one of the shafts 31, being extended and further provided with the sprocket 50, which is driven by the chain 35, 80

The upper member of the housing 29, is provided with the bearing bracket 36, in which is mounted the V-shaped idle and retaining wheel 37.

85 Rotatably and detachably mounted upon and frictionally driven by the wheels 32, and 37, is the revolving circular ring 38, which is provided with the V-shaped groove in the periphery thereof for the reception of and 90 adapted to be retained and driven by said friction wheels 32.

95 Integral with the front surface of the revolving ring 38, and directly opposite each other are the bearing lugs 39, in which are pivoted the swing compressor arms 40, which are formed with the bearings 41 in their outer ends. In the bearings 41 are rotatably mounted the shafts 42, upon which are secured the bevel gears 43, which are in mesh with the small gear 44. The gear 44 is formed with an axial orifice in the center thereof for the passage of the wire or conductor 3, and is rigidly retained in the box 45, which is provided on the cross-bar 46, 105 of the lower housing member, and secured by the set screw 47.

110 Upon the outer ends of the shafts 42, adjacent to the bevel gears 43, are secured the compressor disks 48, which are formed with the beveled edges 49, which are parallel with each other at their contact with the wire and are in contact with and rotate about the surface of the asbestos coated wire 3, as the wire 3 travels forward through the 115 orifice in the gear 44 and between the surfaces 49 the ring 38 is rotated about the wire and the bevel gears 43 are revolved by said ring being rotated about the stationary gear 44. The centrifugal force created by 120 the revolution of said ring 38 will tend to throw the bevel gears outward, and as the swing arms 40 are pivoted to one side of the center of gravity of said gears 43, the outward swing of said gears 43, will only 125 serve to bring the compressor surfaces into closer contact with the coated surface of the wire, as the small gear 44, prevents them from going farther.

130 It will thus be seen that there is produced

a rotary compression upon the covering of the wire, that will automatically adjust itself to all variations in the thickness of the insulation or any lumps of foreign matter 5 therein contained; and also the wire covering will be compressed with equal facility upon flat wire, as the compressors will readily adapt themselves to the greater diameter of the wire, and the centrifugal force 10 will bring their faces nearer together for the lesser diameter of said wire. In this connection it may be further stated that in compressing insulating material upon a conductor that it is impracticable to employ 15 for this purpose rolls bearing upon the conductor in peripheral alinement in order that each may act uniformly on the insulation, or to employ a series of compressing plates or dies to operate under spring tension as 20 are now used on machines of this class when the conductor is rotated as it progresses through the machine, as there always remains in asbestos fiber pieces of hard fiber and foreign matter that are not crushed and 25 when they are deposited upon the conductor in a diagonal or transverse relation to the axis of said conductor, they are struck by the rolls or compression plates and tend to carry the fiber from the conductor or to 30 reduce the thickness of its deposit, thus either entirely stripping the insulating material from the conductor or reducing the quality of the finished product, and it will thus be readily seen that my invention over- 35 comes these obvious objections.

Having thus described my invention what I claim as new and desire to secure by Letters Patent is:—

1. In a machine of the class described, 40 the combination with means for depositing flocculent insulating material upon the surface of the wire or conductor which may be previously coated with an adhesive composition, of mechanism for compressing said 45 insulating material upon said wire, comprising a housing mounted upon said machine in axial relation to and surrounding said wire or conductor, a ring surrounding said wire or conductor and rotatably mounted in 50 said housing, compressors pivotally mounted

upon said ring and adapted to be brought into a rolling and pressing contact by the centrifugal force caused by the revolution of said ring.

2. In a machine of the class described, in 55 combination with means for feeding the conductor, and means for applying asbestos fiber in a flocculent state upon the surface of said conductor, of a ring encircling said conductor and adapted to be revolved about 60 said conductor in an axial relation thereto, arms pivoted to said ring, revolving compressors mounted in said arms and adapted to be rotated in contact with said asbestos covered wire as said ring is revolved about 65 said traveling wire, and means whereby the compressing mechanism adjusts itself to variations in thickness of said asbestos fiber.

3. An insulating mechanism for use in wire covering machines, comprising a housing mounted upon said covering machine, a ring surrounding the wire and rotatably mounted within said housing and adapted to turn about said wire, arms pivoted to said ring and in a radial relation with the 70 center thereof, gears rotatably mounted upon the ends of said arms and meshing with a stationary gear mounted upon said housing, compressor disks carried by said revolving gears and adapted to be revolved 75 in contact with the surface of said insulation upon said wire, means for rotating said ring within said housing and means for feeding the wire through said ring and housing in an axial relation thereto. 80

4. In a wire coating machine, the combination of a rotatable carrier, means for rotating said carrier, a rubbing device on said carrier, and means for so associating the carrier, the rubbing device and the wire 85 as to cause the rubbing device to bear upon the wire by centrifugal force when the carrier is rotated.

In testimony whereof I affix my signature in presence of two witnesses.
